ELECTROMAGNETIC DEVICE WITH
ARMATURELaurence C. Biggle, Altadena, Calif., assignor to
General Controls Co., Glendale, Calif., a corpora-
tion of California

Application February 20, 1945, Serial No. 578,827

9 Claims. (Cl. 175—336)

1

My present invention relates to electromagnetic devices of the type which comprises a rockable armature for operating electrical contacts, pilot-valve means, or the like.

It is an object of this invention to provide a device of the character described which is so constructed that transfer of magnetic flux between the armature and the core of the device is improved.

More specifically it is an object to provide an electromagnetic device comprising a U-shaped core and an armature fulcrumed on the end of one of the side arms of the core, and means for increasing flux transfer between the armature and the fulcrum end of the core without adversely affecting mechanical movement of the armature.

Another object is to provide, in a device of the character described in the preceding object, improved means for retaining the armature in operative relation to the core.

Still another object is to provide improved means for preventing relative flexure of the side arms of the U-shaped core.

Other objects and advantages of the invention will be found in the description, the drawing, and the claims; and, for full understanding of the invention, reference is to be had to the following detailed description and accompanying drawing, wherein:

Figure 1 is a perspective view of an electromagnetic device embodying the invention;

Figure 2 is an exploded view of the device shown in Fig. 1;

Figure 3 is an enlarged side elevation of the device of Fig. 1 as mounted on a base, the bracket 28 and armature-retaining clip 24 being shown in section;

Figure 4 is a detail view of the pole piece 16; and

Fig. 5 is a fragmentary bottom view of the structure shown in Fig. 3.

Referring first more particularly to Fig. 2 of the drawing, the numeral 11 indicates a generally U-shaped electromagnet core having a rectangular lower side-arm 12 and a cylindrical upper side-arm 13 which are joined by a triangular end portion 14; the parts preferably being integrally formed from a single piece of metal so as to avoid the possibility of air-gap losses. Around the upper side-arm 13 is an energizing coil 15; the mean turn diameter (and, consequently, the electrical resistance) of the winding of this coil being relatively small due to the small diameter of the arm 13, as indicated in the draw-

2

ing. On the end of arm 13 is a pole piece 16 (shown per se in Fig. 4) having an opening for tightly receiving the arm so that, after the coil is mounted, the pole piece is pressed-on to a position wherein its outer surface, or pole face, is exactly aligned with the end of the lower arm 12. Closely fitting the pole piece 16, and in abutting relation to shoulders 17 (Fig. 4) formed on opposite sides thereof, is a plate 18 of non-magnetizable metal.

At the end of the lower side-arm 12 of the core, and preferably formed integrally therewith, is a lateral extension 19. The ends of arm 12 and extension 19 are oppositely beveled to form, respectively, inclined surfaces 20 and 21 which define between them a knife-edge fulcrum 22. This fulcrum, while conveniently termed as "knife-edged," is preferably quite blunt and has a surface or land of about 0.020 inch in width.

The fulcrum 22 serves as a support for a blade-like armature 23 which is retained in position with respect to the core by a generally U-shaped wire clip 24, the side arms of the clip extending freely through notches 25 in opposite edges of the armature and into grooves 26 formed in the extension 19 adjacent the fulcrum 22. The grooves 26 are of such size that the clip fits snugly within them so that the clip is held temporarily in armature-retaining position during assembly. For convenience of handling, the clip is provided with a forked projection 27.

Generally indicated at 28 in Fig. 2 is a bracket, preferably formed of non-magnetizable material such as brass. To attach this bracket to the electromagnet core (after the armature and retaining clip are in position) the bracket is moved directly upwardly from its position as shown in Fig. 2, the lower portion of the armature passing through the rectangular opening 29. Formed at 40 opposite sides of the bracket opening 29 are recesses 30 which are adapted to receive and hold the outwardly-bent extremities 31 of the side arms of the armature-retaining clip 24 when the bracket is in its final position (as shown in Fig. 1) in engagement with the underside of the lower side-arm 12 of the core. The bracket 28 has a pair of upstanding (as seen in Fig. 2) arms 32 which are flexed slightly apart, during assembly of the bracket, to permit their channeled upper portions to receive lugs 33 formed on opposite sides of the plate 18; these lugs, when the bracket reaches its final position, snapping into conforming openings 34 in the bracket arms. When the bracket is in position, it is secured to the core by screws 35 (Fig. 3) which pass through openings

36 in the bracket and are threaded in corresponding openings in the core side-arm 12. The device, as assembled, is shown in Fig. 1. By the cooperation of the bracket side-arms 32 with the plate 18, relative movement of the core side-arms, such as might be caused by a fall or jar, is prevented; accurate alignment of the polar surface of pole piece 16 with the fulcrum 22 thus being preserved.

In Fig. 3, the electromagnetic device is shown mounted on an apertured base plate 37; there also being shown in this figure a pair of jets 38 and 39 with which the lower end portion of the armature cooperates to serve as the closure of a conventional three-way pilot valve comprising the jets. This arrangement is only by way of illustration and obviously other control means, such as electrical contacts, could be substituted for the jets. As shown in Fig. 3, the armature 23 is biased into engagement with jet 39, and with the fulcrum 22, by the force of a compression spring 40 which is clamped at one end to the base plate 37 by an upset portion 41 of the bracket 28, the pointed other end of the spring resting in a small depression 42 (Fig. 2) in the armature. When the core 11 is energized by passage of current through coil 15, the armature is attracted toward the pole piece 16 and into engagement with the other jet 38; the armature then being slightly spaced from the pole piece.

As is seen in Fig. 3, the surface 21 (Fig. 2) defined by the extension 19 is spaced by only a minute distance from the armature when the same is in its unattracted position, so that conduction of magnetic flux adjacent the fulcrum is increased and the pull-in value of the energizing current correspondingly decreased. Similarly, the surface 20 at the opposite side of the fulcrum is inclined at only a small angle. For the sake of clarity, the angles of inclination of the surfaces 20 and 21, as shown in the drawing, have been exaggerated; the inclination of these surfaces, in a practical embodiment of the invention, being such that the space between the armature and the outer extremity of surface 21 is about 0.002 inch, and that at surface 20 about 0.010 inch, when the armature is rocked toward the respective surfaces. Due to this arrangement of the polar surfaces 20 and 21, and also due to the enlarged polar surface provided by the pole piece 16, the effectiveness and sensitivity of the device is considerably increased.

The specific embodiment of my invention herein shown and described is obviously susceptible of modification without departing from the spirit of the invention, and I intend therefore to be limited only by the scope of the appended claims.

I claim as my invention:

1. In an electromagnetic device: a generally U-shaped core, an energizing coil for said core, and a blade-like armature rockably supported on the end of one of the side arms of the core and extending adjacent the end of the other of the side arms for attraction theretoward when the core is energized, the end of said one of the side arms being formed to provide a fixed knife-edge fulcrum for the armature, the material of said one of the side arms on the side of said fulcrum away from the other of the side arms providing a flat surface spaced by a minute distance from the armature when, upon deenergization of the core, the armature is rocked toward said surface, said material of said one of the side arms being so intimately united with the remainder of the

side arm that there is no air-gap therebetween.

2. In an electromagnetic device: a generally U-shaped core, an energizing coil for said core, and a blade-like armature rockably supported on the end of one of the side arms of the core and extending adjacent the end of the other of the side arms for attraction theretoward when the core is energized, the end of said one of the side arms being formed to provide a fixed fulcrum for the armature, said one of the side arms having at said end thereof a lateral extension in a direction away from the other of the side arms, said extension being of magnetizable material and providing a flat surface of relatively large area spaced by a minute distance from a portion of the armature when, upon deenergization of the core, the armature is rocked toward said surface, said extension being so intimately united with the side arm from which it extends that there is no air-gap therebetween.

3. In an electromagnetic device: a generally U-shaped core, an energizing coil for said core, and a blade-like armature rockably supported on the end of one of the side arms of the core and extending adjacent the end of the other of the side arms for attraction theretoward when the core is energized, the end of said one of the side arms being formed to provide a fixed knife-edge fulcrum for the armature, the material of said one of the side arms being intimately united with the side arm and beveled to provide a pair of inclined flat surfaces on opposite sides of said knife-edge, the one of said surfaces away from said other of the side arms being relatively large in area and spaced by a minute distance from the armature when, upon deenergization of the core, the armature is rocked theretoward.

4. In an electromagnetic device: a generally U-shaped core, an energizing coil for said core, and a blade-like armature rockably supported on the end of one of the side arms of the core and extending adjacent the end of the other of the side arms for attraction theretoward when the core is energized, the end of said one of the side arms being formed to provide a fixed knife-edge fulcrum for the armature, the material of said one of the side arms being intimately united with the side arm and beveled to provide a pair of inclined flat surfaces on opposite sides of said knife edge, said material being so extended in a direction away from the other of the side arms that the one of said surfaces there defined is of relatively large area, said one of the surfaces being spaced by a minute distance from a portion of the armature when, upon deenergization of the core, the armature is rocked theretoward.

5. In an electromagnetic device: a generally U-shaped core, an energizing coil for said core, and a blade-like armature rockably supported on the end of one of the side arms of the core and extending adjacent the end of the other of the side arms for attraction theretoward when the core is energized, the end of said one of the side arms being formed to provide a fixed knife-edge fulcrum for the armature, said one of the side arms having at said end thereof a lateral extension in a direction from the other of the side arms, said extension being integral with the side arm and providing a flat surface of relatively large area spaced by a minute distance from a portion of the armature when, upon deenergization of the core, the armature is rocked theretoward, said end of the other of the side arms being formed to provide a surface having a large

area in flux-transfer relation to the adjacent surface of the armature.

6. In an electromagnetic device: a generally U-shaped core; an energizing coil for said core; a blade-like armature rockably supported on the end of one of the side arms of the core and extending adjacent the end of the other of the side arms for attraction theretoward when the core is energized; and retaining means for the armature, comprising a generally U-shaped clip the side arms of which freely extend through openings formed at opposite margins of the armature on the pivotal axis thereof and are mounted in openings in the corresponding margins of said one of the core side-arms.

7. In an electromagnetic device: a generally U-shaped core; an energizing coil for said core; a blade-like armature rockably supported on the end of one of the side arms of the core and extending adjacent the end of the other of the side arms for attraction theretoward when the core is energized; and retaining means for the armature, comprising a generally U-shaped clip the side arms of which freely extend through openings formed at opposite margins of the armature on the pivotal axis thereof, and a bracket fastened to said one of the core side-arms, the free ends of the side arms of the clip being outwardly bent in the plane of the clip, said bracket having openings for receiving said outwardly-bent end portions of the clip.

8. In an electromagnetic device: a generally U-shaped core; an energizing coil for said core; a blade-like armature rockably supported on the end of one of the side arms of the core and extending adjacent the end of the other of the side arms for attraction theretoward when the core is energized; and retaining means for the armature,

ture, comprising a generally U-shaped clip the side arms of which freely extend through openings formed at opposite margins of the armature on the pivotal axis thereof and are closely received in grooves formed in the corresponding margins of said one of the core side-arms and a bracket fastened to said one of the core side-arms, the free ends of the side arms of the clip being outwardly bent in the plane of the clip, said bracket having recesses for receiving said outwardly-bent end portions of the clip.

9. In an electromagnetic device: a generally U-shaped core; an energizing coil for said core; a blade-like armature rockably supported on the end of one of the side arms of the core and extending adjacent the end of the other of the side arms for attraction theretoward when the core is energized; and means for preventing relative flexure of said side arms, comprising a plate apertured to fit over said end of the other of the side arms, and a bracket secured to said one of the side arms and having spaced portions extending toward said other of the side arms for engagement with opposite sides of said plate.
